ELECTRICAL CONTROL CIRCUIT

Frank J. Somers, Rockville Centre, N. Y., assignor to Radio Corporation of America, a corporation of Delaware

Application December 27, 1941, Serial No. 424,645

9 Claims. (Cl. 179—171)

This invention relates to electrical control circuits and more particularly to the method and apparatus for controlling "peak-to-peak" ratios in amplifier systems containing non-linear amplifiers.

In certain amplifying systems, such as, for example, those used in television, it is desirable to deliberately introduce non-linear amplification in order to modify the signals representing tone gradations in the picture to be reproduced. Thus, for example, if the picture contains a "shadow" area in which it is desirable to reproduce all the detail in the area, then the signals representative of the "shadow" area are expanded or amplified in a greater proportion than the signals in the "white" portion of the picture. Alternatively, it may be desirable to suppress the "shadow" detail entirely and this can be done by reducing the amplification of the signals representative of "black" and increasing the amplification to a greater degree of the signals representative of "white." Unfortunately, the introduction of such a control of amplification, commonly called in television, "gamma" control, changes the ratio of the "peak-to-peak" input signal voltage to the "peak-to-peak" output signal voltage. The change in ratio results in improper reproduction unless corrective means are introduced to hold the ratio constant regardless of the value of gamma control. While this signal amplitude correction can be accomplished manually, such control is unsatisfactory since the operator, who may be at a remote control point, has no information except his judgement of a reproduced picture as to how much correction to introduce. In addition, it is difficult to follow manually any rapid changes in signal level. My invention overcomes the shortcomings of such manual control systems, since my invention provides automatic control to give a constant ratio of "peak-to-peak" input to output.

Furthermore, as is well known in television, certain types of television camera tubes have non-linear response to the intensity of illumination. Similarly the grid-voltage versus light-output characteristic of most television reproducer tubes have a non-linear shape. The overall result of combining such non-linear elements in a complete television system is to accentuate the contrast in the range corresponding to one group of light values to the detriment of reproduction of gradations in another group of light values. It thus becomes necessary to provide a type of amplitude distortion complementary to the video faithfully reproduced at the television receiver.

Such correction may be applied at one or more points in the video amplifying system.

In general, it is preferable to distribute the complementary correction so that part of it is applied at the transmitter and part of it is applied at the receiver. Thus, that part of the video signal corresponding to the darker parts of the picture can be made to give a higher average percentage modulation if the correction is split 5 between the receiver and the transmitter than if the correction were applied at only the transmitter or the receiver. There results from this division of correction an advantage in that the signal-to-noise ratio at the receiver can be improved. By providing automatic control to maintain the "peak-to-peak" signal ratio constant, the advantages of non-linear amplification can be enhanced. Accordingly, it is the main object 10 of my invention to provide a new, useful and improved amplifying system.

Another object of my invention is to provide a method and apparatus to improve amplifying systems.

Another object of my invention is to provide 15 a method of amplification control such that changes in gamma can be effected without disturbing the modulation conditions established at a transmitter.

A still further object of my invention is to provide 20 a new method and apparatus for maintaining the "peak-to-peak" ratio of input to output voltage of a non-linear amplifying system constant.

Another object of my invention is to provide 25 an improvement in television amplifying systems.

Other objects of my invention will become at 30 once apparent to those skilled in the art upon reading the following detailed description when taken together with the drawing.

In the drawing, there are two figures of which 35 Figure 1 shows graphically the relation between brightness and output of a camera tube, as well as the non-linear characteristic of an amplifier 40 used in my invention; while Figure 2 shows schematically apparatus useful in practicing my new invention and which includes circuit arrangements for maintaining the "peak-to-peak" ratio constant.

Referring now to Figure 1, I have shown at 45 the characteristic of a television camera tube for example, an Iconoscope, which relates the brightness to the output of the tube in volts. The abscissa is shown in units of brightness such as 50 lumens per square foot, while the ordinate is in

units of volts output. The curve B shown at 3 gives the non-linear characteristic of a gamma amplifier and has for its abscissa units of volts input and for its ordinate, output in volts. It will be noted that the two curves have complementary curvature so that if the output of the camera tube shown at A is fed to a gamma amplifier having a characteristic B, the overall characteristic will be substantially linear. It will be observed, however, that a unit increment of input voltage at B provides an incremental output whose value will vary with the mean value of the incremental voltage supplied at the input. For example, an input difference or increment *ab* produces an incremental output *de*, while an incremental input *bc* equal to *ab* will produce an incremental output *ef*. It will at once be apparent therefore that the ratio of

$$\frac{de}{ab}$$

is considerably smaller than the ratio of

$$\frac{ef}{bc}$$

It will thus be clear that the "peak-to-peak" ratio changes with the value of the average brightness in the picture, which is represented by the direct current component in the video signal. Moreover, it will be appreciated that the characteristic curve of the gamma amplifier 1, may be altered and that such an alteration alone would also produce a change in the ratio of the two "peak-to-peak" values. Since the "peak-to-peak" value affects the percentage modulation at the transmitter, it is necessary to insure that the ratio of the "peak-to-peak" input to the "peak-to-peak" output remains constant in order to insure that proper modulation of the transmitter is maintained. It is therefore one purpose of the present invention to provide means for altering the relative modulation ratios for various picture tonal values while keeping the total transmission modulation constant.

Turning now to Figure 2, I have shown video amplifier 5 receiving the input from the television camera, for example, or its pre-amplifier, and feeding its output to the gamma amplifier 1. The gamma amplifier is an amplifier having a characteristic 3 shown in Figure 1. The output of the gamma amplifier is fed to an automatic volume control amplifier 9 which in turn has its output connected to a second video amplifier 11. The output of this video amplifier is then fed to a transmission line to be further amplified and transmitted by the video radio transmitter. A portion of the output energy of the video amplifier 5 is fed through the condenser 13 to the amplifier tube 15 provided with suitable biasing and decoupling networks comprising the resistors 61, 63, 67, 69 and the condenser 65. The amplifier tube 15 has a gain of approximately unity, and operates primarily as a phase inverter tube, out-of-phase potentials being available from the anode and cathode of the tube. Push-pull signals available from the cathode and anode of tube 15 are applied to a bridge type rectifier 23 through the capacitors 19 and 21, the capacitors 19 and 21 serving to avoid any D. C. connections between the tube 15 and the other parts of the control circuit.

The polarity of the rectified voltage is as indicated in Figure 2. The rectified voltage ap-

pears across the network including the condenser 39 and the resistor 41 which network is connected between the diode 37 and the network comprising the parallelly connected condenser 43 and resistor 45. There is thus provided across the terminals of the network 39, 41 a D. C. potential which is proportional to the "peak-to-peak" video voltage output of the amplifier 5. A portion of the output energy of the video amplifier 11 is similarly fed through condenser 25 to a thermionic amplifier and phase inverter tube 27 which is also provided with suitable biasing and decoupling network including the resistors 71, 73, 77, 79 and the condenser 75. The energy appearing at the anode and cathode of tube 27 is fed through the condensers 31 and 33 to the bridge rectifier 35 to produce a D. C. potential of the polarity as indicated in the Figure 2. This D. C. potential which is proportional to the "peak-to-peak" voltage output of the amplifier 11 is supplied to the anode of the tube 37 and to the junction point of the parallelly connected condenser 43 and resistor 45 connected to the biasing voltage. From the common junction point of the networks 39-41 and 43-45 a connection is brought to the amplifier tube 47 whose plate is supplied by voltage through the resistor 49 and from the plate of which a low pass filter comprising resistors 51, 53 and condensers 55 and 57 is connected. The output of the filter feeds the automatic volume control amplifier 9. The amplifiers 9 and 11 are initially adjusted so as to provide excess gain over that required to supply a signal to the transmission line sufficient to modulate the transmitter one hundred percent. In operation then, the voltage across the rectifier 35 will exceed the voltage across the rectifier 23 and overcome the bias produced by the rectifier 23 across the network 39-41. As a result, current will flow from the rectifier 35 through the loop including the impedances 43 and 45 producing, at the junction point of the two impedance networks, a positive voltage which is supplied to the grid of the tube 47. The tube 47 thus draws more current, producing an I. R. drop in the resistor 49, so as to decrease the voltage supplied to the automatic volume control amplifier 9. As is well known, under these conditions, the gain of the amplifier 9 will be reduced and this reduction in the gain of the amplifier 9 will take place up to the time that the voltages produced by the rectifiers 23 and 35 balance each other so that the potential on the grid of the tube 47 maintains the gain of the amplifier 9 to keep the two rectifiers in balanced condition. It will, of course, be appreciated that the time constants of the impedance networks 39-41 and 43-45 and the low pass filter 51-53, 55-57 are chosen, so as to insure that the change of the gain of the amplifier 9 takes place over one or more frames of the pictures to avoid abrupt changes in brightness in the received picture. Also, in the interest of good design, it is desirable while maintaining the proper R. C. time constants to make resistor 45 about one hundred times as large as resistor 41 such that when rectifier 37 draws current, the major portion of the potential drop will be produced across the terminals of the R. C. network 43, 45. Under these conditions, the current through the tube 37 will not appreciably alter the potential across the impedances 39 and 41 so that this potential continues to represent the "peak-to-peak" input voltage to the ampli-

fiber 5. As an example, practical values for a time constant of one-tenth of a second would be

Resistor 41=20,000 ohms
Condenser 39=5 mfd.
Resistor 45=2 megohms
Condenser 43=0.05 mfd.

Likewise, it will be appreciated that it is convenient to arrange the circuits such that balance is effected when the "peak-to-peak" voltage fed to the gamma amplifier 7 is equal to the "peak-to-peak" voltage at the output of the video amplifier 11.

Again, it will be noted that the units 5, 7, 9 and 11 are conventional ones ordinarily included in a television chain, and consequently, the only additional apparatus required for affecting the automatic control of the ratio of "peak-to-peak" voltages of the tubes 15, 27, 47 and 37 and their associated components. Accordingly, these elements of the control circuit may be built into one unit which can be added to any existing television amplifier chains to improve operation. It will be appreciated, of course, that while the tubes 15, 27 and 47 have been shown as triodes, this is merely by way of example and pentodes or any other thermionic amplifier tubes may be used. Likewise, while the tube 37 is shown as a diode, it will be clear that a triode type rectifier may be used and this is also true of the rectifier bridges 23 and 35. Again it will be appreciated that while amplifiers 5 and 11 have been shown in Figure 2, these amplifiers may be omitted in those cases where the signal level is sufficient to give ample rectified voltages for comparison with each other.

Various alterations and modifications of the present invention may become apparent to those skilled in the art and it is desirable that any and all such modifications and alterations be considered within the purview of the present invention except as limited by the hereinafter appended claims.

What I claim is:

1. The method of maintaining a constant ratio between the "peak-to-peak" value of the energy at the input and output of a non-linear amplifier system, which includes the steps of supplying wave energy to be amplified, amplifying the supplied energy non-linearly with respect to the amplitude of the supplied energy, amplifying the non-linearly amplified energy, deriving energy proportional to the "peak-to-peak" value of the supplied energy, deriving energy proportional to the "peak-to-peak" value of the non-linearly amplified energy, comparing the two derived energies and controlling the amplification of the non-linearly amplified energy in accordance with the difference between the compared energies.

2. The method of maintaining a constant ratio between the "peak-to-peak" value of the energy at the input and output of a non-linear amplifier system, which includes the steps of supplying wave energy to be amplified, amplifying the supplied energy non-linearly with respect to the amplitude of the supplied energy, amplifying the non-linearly amplified energy, deriving a direct current potential proportional to the "peak-to-peak" value of the supplied energy, deriving a direct current potential proportional to the "peak-to-peak" value of the non-linearly amplified energy, comparing the two derived potentials and controlling the amplification of the non-linearly amplified energy in accordance with the difference between the compared potentials.

3. The method of maintaining the "peak-to-peak" ratio of the input and output energy of a non-linear amplifier system constant, which includes the steps of supplying wave energy to be amplified, amplifying the supplied energy non-linearly with respect to the amplitude of the supplied energy, amplifying the non-linearly amplified energy, full wave rectifying a portion of the supplied energy to derive a potential proportional to the "peak-to-peak" value of the supplied energy, full wave rectifying a portion of the non-linearly amplified energy to derive a potential proportional to the "peak-to-peak" value of the amplified non-linear energy, comparing the two derived potentials and controlling the amplification of the non-linearly amplified energy in accordance with the difference between the compared potentials.

4. A constant input to output "peak-to-peak" energy ratio amplifying system comprising means for supplying wave energy to be amplified, means for amplifying the supplied energy non-linearly with respect to the amplitude of the supplied energy, means for amplifying the non-linearly amplified energy, full wave rectifying means for deriving energy proportional to the "peak-to-peak" value of the supplied energy, full wave rectifying means for deriving energy proportional to the "peak-to-peak" value of the non-linearly amplified energy, means for comparing the two derived energies and means for controlling the amplification of the non-linearly amplified energy in accordance with the difference between the compared energies.

5. A constant input to output "peak-to-peak" energy ratio amplifying system comprising means for supplying wave energy to be amplified, means for amplifying the supplied energy non-linearly with respect to the amplitude of the supplied energy, means for amplifying the non-linearly amplified energy, full wave rectifying means for deriving a direct current potential proportional to the "peak-to-peak" value of the supplied energy, full wave rectifying means for deriving a direct current potential proportional to the "peak-to-peak" value of the non-linearly amplified energy, means for comparing the two derived potentials and means for controlling the amplification of the non-linearly amplified energy in accordance with the difference between the compared potentials.

6. A constant input to output "peak-to-peak" energy ratio amplifying system comprising means for supplying wave energy to be amplified, means for amplifying the supplied energy non-linearly with respect to the amplitude of the supplied energy, means for amplifying the non-linearly amplified energy, means including a full wave rectifier for rectifying a portion of the supplied energy to derive a potential proportional to the "peak-to-peak" value of the supplied energy, means including a full wave rectifier for rectifying a portion of the non-linearly amplified energy to derive a potential proportional to the "peak-to-peak" value of the amplified non-linear energy, means for comparing the two derived potentials and means for controlling the amplification of the non-linearly amplified energy in accordance with the difference between the compared potentials.

7. A non-linear amplifying system comprising a source of signals to be amplified, a non-linear amplifier, a linear amplifier connected between said source of signals and said non-linear amplifier, means to amplify energy from said non-

linear amplifier, full wave rectifying means for deriving a potential proportional to the "peak-to-peak" value of the energy from said source of signals, full wave rectifying means for deriving a potential proportional to the "peak-to-peak" value of the non-linearly amplified signals, means to compare the said derived potentials, and means to control the gain of said amplifying means in accordance with the difference between the compared potentials.

8. A non-linear amplifying system comprising a source of signals to be amplified, a non-linear amplifier, a linear amplifier connected between said source of signals and said non-linear amplifier, means to amplify energy from said non-linear amplifier, opposed unilateral conducting means for developing a potential proportional to the "peak to-peak" value of the energy from said source of signals, opposed unilateral conducting means for developing a potential proportional to the "peak-to-peak" value of the non-linearly

amplified signals, means to compare the two developed potentials, and means to control the gain of said amplifying means in accordance with the difference between the compared potentials.

9. A non-linear amplifying system comprising a source of signals to be amplified, a non-linear amplifier, a linear amplifier connected between said source of signals and said non-linear amplifier, means to amplify energy from said non-linear amplifier, a first full wave rectifying means for generating a potential proportional to the "peak-to-peak" value of the energy from said source of signals, a second full wave rectifying means for generating a potential proportional to the "peak-to-peak" value of the non-linearly amplified signals, means to compare the two generated potentials, and means to control the gain of said amplifying means in accordance with the difference between the compared potentials.

RANK J. SOMERS.
